UNITED STATES PATENT OFFICE.

ALBERT T. NEWMAN, OF GREELEY, KANSAS.

GAS-REGULATOR.

No. 901,981.

Specification of Letters Patent.

Patented Oct. 27, 1908.

Application filed March 11, 1907. Serial No. 361,807.

To all whom it may concern:

Be it known that I, ALBERT T. NEWMAN, a citizen of the United States, residing at Greeley, in the county of Anderson and State 5 of Kansas, have invented a new and useful Improvement in Gas-Regulators, of which the following is a specification.

This invention relates generally to gas regulators and more particularly to a regulator adapted for use in connection with a gas main, the object being to provide a low pressure gas regulator specially useful upon natural gas mains and useful for the house, office or any other place where an even flow 15 of gas is required.

Another object of the invention is to provide a gas regulator in which the parts shall be so constructed and arranged that leakage will be impossible and one in which the 20 slightest variation from normal pressure will serve to operate the valves and with these objects in view, the invention consists in the novel features of construction, combination and arrangement, all of which will 25 be fully described hereinafter and pointed out in the claims.

In the drawings forming a part of this specification: Figure 1 is a vertical sectional view of a gas regulator constructed in accordance with my invention and showing the position of the various parts, when the pressure is normal. Fig. 2 is a similar view showing the position of the parts when the pressure has become abnormal. Fig. 3 is a 35 horizontal sectional view on the line 3—3 of Fig. 2.

In the practical embodiment of my invention, I employ a box-like casing A having an opening A' at one side which opening is 40 surrounded by a threaded box A² into which screws the delivery pipe B. The opposite side of the casing is flanged as shown at A³ and securely bolted to this flange side of the casing is a metal plate C suitable packing C' being interposed to provide an absolutely 45 tight joint. This plate C has an opening C² arranged directly opposite the opening A' and surrounded by a threaded sleeve or boss C³ into which screws the supply pipe D, and 50 a short pipe E is also screwed in said opening and forms a continuation of the pipe D, a suitable packing E' being interposed between the ends of the pipes E and D. This pipe E extends into and supports the valve 55 box F, said box having a detachable top F' and the top and bottom of the box are formed

with openings G to permit the escape of the gas, which after passing through the pipes D and E and out through the valve box G fills the casing A and eventually passes out 60 through the delivery pipe B.

The upper end of the casing A is provided with a diaphragm chamber consisting of the integral lower portion H and the upper portion H' securely bolted to the lower portion and rigidly holding the diaphragm I, between the two sections, and rigidly connected to the said diaphragm is a vertically depending stem K, carrying the valves L and M thereon, one of said valves being arranged in 70 the valve box and the other below the said valve box as shown and it will be noted that the valve stem is guided in its movements by means of the guide brackets N attached to the top and bottom of the box as most clearly 75 shown.

Whenever the pressure within the valve casing becomes too strong the diaphragm is of course lifted and the valves seat in the opening G and cut off the flow of gas and 80 as soon as the pressure becomes normal the diaphragm will drop and consequently the valve stem and valves and more gas will be permitted to flow into the casing.

For the purpose of adjusting the pressure 85 upon the diaphragm so that it will become operative at any predetermined pressure, I employ a spiral spring O the lower end of which is adapted to surround the upper end of the valve stem and bear upon the central 90 portion of the diaphragm, the upper end of said spring bearing against an adjustable screw P which works through the top central portion of the section H' and by raising or lowering the screw the tension upon 95 the spring can be regulated and consequently the pressure of the diaphragm adjusted to any desired point.

It will thus be seen that I provide an exceedingly simple strong and durable form 100 of gas regulator, one which will effectively cut off the flow of gas the moment the pressure becomes abnormal, one in which the possibility of leakage is reduced to a minimum and one which owing to small number 105 of parts and simplicity of construction, will be rendered easy and efficient in operation.

Having thus fully described my invention, what I claim as new and desire to secure by Letters Patent, is:—

A gas regulator comprising a box like casing having a removable side, said re-

movable side having a threaded opening, a supply pipe screwed into said opening, a short section of pipe screwed also into said opening from the interior of the box, a 5 valve box carried at the inner end of said short section of pipe, said valve box having a detachable top, the top and bottom of the box being provided with openings, valves adapted to close said opening, the stem 10 carrying said valves the guides carried by the valve box and in which the valve-stem works, a diaphragm arranged in the upper

portion of the casing and to which the valve stem is connected, an adjustable spring pressing means operating upon the opposite side of the diaphragm and a delivery pipe leading from the box like casing, all of said parts being constructed, arranged and adapted to operate substantially as shown and described.

ALBERT T. NEWMAN.
